[57] CLAIM

The ornamental design for a telephone base, as shown and described.

DESCRIPTION

FIG. 1 is a top, front and side perspective view of a telephone base showing our new design;

FIG. 2 is a top plan view thereof;

FIG. 3 is a side elevational view of the telephone base, the opposite side being a mirror-image thereof; and, FIG. 4 is an end elevational view of the telephone base, the opposite end being identical therewith.

The broken line showing of a handset and cord in FIG. 1 is for illustrative purposes only and forms no part of the claimed design.
